UNITED STATES PATENT OFFICE.

CONRAD J. KORTZ, OF CLEVELAND, OHIO.

COMBINED BILL-FILE AND MAILING-CARD.

1,217,962.

Specification of Letters Patent.

Patented Mar. 6, 1917.

Application filed May 20, 1916. Serial No. 98,722.

To all whom it may concern:

Be it known that I, CONRAD J. KORTZ, a citizen of the United States, residing at Cleveland, in the county of Cuyahoga and State of Ohio, have invented certain new and useful Improvements in Combined Bill-Files and Mailing-Cards, of which the following is a specification.

My invention comprises a bill file particularly constructed to be folded and sealed to facilitate transmission through the mails, and the specific form of the invention shown and described herein involves the use of an impaling hook which is pivotally mounted on a foldable card to serve as a bill holder and also as a sealing member for the folded card.

In the accompanying drawings, Figure 1 is a plan view of my improved mailing card and bill file in a folded state. Fig. 2 is a perspective view of the device partly unfolded in full lines and entirely unfolded in dotted lines. Fig. 3 is a longitudinal section of the folded article on line 3—3, Fig. 1.

My combined mailing card and bill file comprises a small paste-board card 2 having a transverse crease at its middle dividing the card into two equal sections adapted to be folded face to face. The opposed faces bear suitable printing and advertising matter, while the outer face 3 of one section is lined and printed to receive a name and address and mailing stamp.

One section of the card is provided with an impaling hook 4 fastened in swiveled and frictional engagement with the bottom side thereof, and the preferred fastening means comprises a relatively large eyelet or rivet 5 located on the median line of the card near one end thereof. Hook 4 is made of stiff spring wire with one end flattened and formed into an eye 6 to afford a stable pivot connection which will not tear loose easily, and when the device is intended to be transported or mailed the prong portion of the hook lies substantially parallel with the main stem and in position to swing over and bear upon the upper face of the superposed card section while the main stem bears against the bottom face of the base section to which it is pivoted. Thus, when the hook is turned to place the folded card therebetween as shown in Figs. 1 and 3, a clamping effect is produced which holds the card shut and prevents free swinging of the

hook, and this clamping effect is enhanced by a hump or offset 7 located in the prong portion of the hook. The pointed end 8 of the hook is also bent inward to either embed itself in the face of the card or to seat within an opening in the top section of the card, and where an exceptionally substantial and reliable holder is desired to pocket pointed end 8 I prefer to use an eyelet 9. A further function of eyelet 9 is to hang the unfolded card upon a nail or hook, and when the bill file is suspended in this way the hook 4 is turned down in a pendent position and the prong portion thereof bent and inclined outward more or less as indicated by the dotted lines, Fig. 2. In this position of parts, bills or papers of any kind may be impaled on the hook, but when the card is folded the hook is also intended to be folded thereupon and to attain this end the pivot point and the length of the hook must bear a definite relation to the ends of the card so as to allow the card to swing within the loop portion of the hook, especially if the hook is to rest on the median line of the card when folded as shown in full lines in Fig. 1. In this way a relatively small package is produced for transmission through the mails; while on the other hand a relatively large printing and advertising space is afforded by the co-extending faces of the two card sections.

What I claim is:

1. A combined bill file and mailing card, comprising superposed sections and an impaling hook mounted on one section and adapted to fold into locking relation with the superposed sections.

2. A combined bill file and mailing card, comprising foldable sections and an impaling hook mounted upon one section and adapted to overlap the other section when folded.

3. A combined bill file and mailing card, comprising a foldable mounting having a folding hook secured in clamping relation to the folded mounting and arranged to impale papers when unfolded.

4. A combined bill file and mailing card, comprising a foldable card having a filing hook pivotally mounted thereon and adapted to bear upon the outer surfaces of the card when folded.

5. A combined bill file and mailing card, comprising a folder having a pointed bill filing hook secured to fold thereupon and

provided with a pocket to seat the point of the hook when the parts are folded.

6. A combined bill file and mailing card, comprising a folder having an opening at 5 one end and a bill hook pivoted at its opposite end, and said bill hook having a bent point adapted to enter said opening when the parts are folded together.

7. A combined bill file and mailing card, 10 comprising a foldable card, and a bill filing hook mounted in folding relation to said card having an offset to bind the parts together.

8. A combined bill file and mailing card, 15 comprising a folded card having a bill filing hook pivotally secured at one free end thereof and bent with its impaling tongue into substantially parallel relation with its main

stem to inclose and grip the folded card therebetween on the median line of said 20 card.

9. A combined bill file and mailing card, comprising a foldable card, a pointed impaling hook having a flattened eye at one end secured in swiveled engagement with 25 one free end of said card, and an eyelet in the opposite free end of the card to hold the pointed end of said hook when the said hook is folded back upon the card.

In testimony whereof I affix my signature 30 in presence of two witnesses.

CONRAD J. KORTZ.
